UNITED STATES PATENT OFFICE.

ALEXANDER BOYNTON, OF SAN ANTONIO, TEXAS.

DEVICE FOR CEMENTING WELLS.

Application filed December 21, 1925. Serial No. 76,839.

This invention relates to a device for cementing wells in accordance with the methods disclosed in my copending applications filed October 1, 1925, Serial Numbers 59,887 and 59,888 and is especially adapted for use in cementing two-string wells although it may be slightly modified and converted to carry out the cementation of one-string wells when desired.

One of the principal objects of the invention resides in the provision of a device wherein the discharge of the cement is controlled by a float valve assembly which acts with a seat arrangement in the well casing and wherein the float valve assembly is so constructed and organized as to afford double assurance of the proper engagement of its valve means with the valve seat arrangement whereby to insure proper action at the proper time.

A further object resides in the provision of a novel form of cement discharge means which comes into action when the cement cannot be discharged below the shoe at the bottom of the cementing device and which will not deteriorate in time and be liable to break through, the cement discharge means being positive in action.

A still further object is to provide an arrangement of back pressure valves which assures effective action in this respect under all circumstances.

Another object is to provide an improved means for locking the casing shoe, couplings and connections against backing off when the signal valve assembly and back pressure valves are being drilled out.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view in transverse vertical section showing a cementing device embodying the present invention, parts being shown in elevation for the sake of illustration,

Figure 2 is a view in elevation showing the device adapted for use with one-string wells,

Figure 3 is a detail view partly in sec-

tion and partly in edge elevation showing one of the cement discharge valves employed in both embodiments of the invention,

Figure 4 is a view thereof in front elevation,

Figure 5 is a sectional view on the line 5—5 of Figure 1, and

Figure 6 is a detail perspective view of one of the locking keys employed.

Referring to the drawings it will be seen that the cementing device is made up of a number of hollow cylindrical sections 1 and 2 coupled together by means of a coupling sleeve 3 which is locked to the sections by means of keys 4 driven in between the coupling sleeve and the sections. The keys 4 are shown in detail in Figure 6 and are shaped to become imbedded in the casing as the keys are driven in place, the outside portions of the keys being received in slots in the coupling. The upper end of the section 1 is provided with a coupling 5 which is locked thereto by other keys 4 and the coupling 5 affords means whereby the cementing device may be connected to the lower end of the well casing.

In the form of the invention shown in Figure 1 a set shoe 6 is threadedly connected to the lower end of the section 2, as indicated at 7, and is locked to the section by means of a number of keys 4* which are identical with the keys 4 except that they are longer.

Between the sections 1 and 2 the flange 8 of a valve seat 9 is clamped and such flange is held in position by means of lock screws 10 co-acting with the coupling 3 and with the flange, as shown in Figure 1. The valve seat 9 has a conoidal portion 11 and an oppositely disposed conoidal portion 12, the conoidal portions 11 and 12 being connected by a short cylindrical portion 13 and in the conoidal portion 12 a valve seat 15 is provided. The flange 8 is connected with the lower end of the conoidal portion 11 by means of a short cylindrical connecting portion 16. A spider 17 is integral with or suitably connected to the flange 8 and to the short cylindrical portion 16 and carries a back pressure valve, designated generally at 18. The present invention not only provides the back pressure valve 18 but also provides a second back pressure valve 20

between the lower end of the section 2 and the set shoe 6 and the back pressure valve 20 is held against spinning by means of lock screws 21.

5. A float valve assembly, designated generally at 25, is provided and includes a stem 26 having a main valve 27 integral with or suitably secured to its lower end, the valve 27 preferably being in the form of a cup designed to co-act with the seat 15. An auxiliary movable valve 28 is provided and also takes the form of a cup or hollow semi-sphere. The valve 28 has a flanged opening 29 at its lower central portion which slidably receives the stem 25. A light coil spring 30 is mounted on the stem and is tensioned to displace the valve 28 upwardly on the stem, the upper end of the spring engaging the valve 28 and the lower end engaging the fixed valve 27. A nut 31 prevents the valve 28 from being displaced from the stem. The valve 28 is designed to co-act with a valve seat 32 fastened to the coupling 5 by means of lock screws 33 as well as by virtue of a threaded connection. The distance between the valves 27 and 28, as normally disposed, is greater than the distance between the seats 32 and 15. The specific gravity of the entire valve assembly is greater than the mud fluid and less than that of liquid cement but the specific gravity of the main valve 27 is slightly greater than the cement while the specific gravity of the auxiliary valve 28 is considerably less than that of the cement.
35. The section 2 is provided with cement discharge openings 35 which have their outer portions or walls countersunk to provide valve seats 36. Metal valves 37 in the form of half spheres co-act with the valve seats 36 and these metal valves 37 are spot welded or otherwise suitably secured to blade spring-like carriers 38, the ends of which have slots 39 co-acting with headed pins 40 fastened to the section 2. The spring carriers 38 are tensioned to hold the valves against their seats 36 but under the influence of a certain predetermined degree of pressure exerted against the valves and the carriers, these spring carriers may be flexed outwardly to permit discharge through the openings 35. Outward flexure is permitted by virtue of the provision of the slots 39.
58. In operation with this form of the invention the cement is placed in the well and the valve assembly 25 is placed thereon and the mud fluid is then pumped down through the well casing until all of the cement has passed out under the set shoe or out through the valve controlled openings 35 as the case may be. It sometimes happens that the casing sticks or freezes in the well in such manner as to prevent the cement from being forced out under the set shoe. This does not impair the

efficacy of applicant's cementing process and device, for under such circumstances the cement is discharged through the valve controlled openings 35.

When all of the cement has passed through the valve seat 15, the valve 27 strikes this seat and unless held unseated by an obstruction prevents further downflow of fluid or liquid and causes the pump to stall, thereby advising the operator that the cementation has been completed. Should the valve 27 fail to seat for any reason the down flow of liquid which follows the same will shift the movable valve 28 downwardly against the tension of its spring 30 to seat the valve 28 against the seat 32 and effect a seal at such point which will cause the pump to stall in the same manner as if the valve 27 had properly engaged its seat 15.

By providing two back pressure valves, in the event of failure of one valve to seat the other will seat whereby double assurance in this respect is had.

This device may be readily converted for use with one string wells omitting the set shoes 6 and the back pressure valve 20 and replacing these parts with a coupling 40 and brass plate barrier 41 as shown in Figure 2. In one string wells the liner 42 is suspended below the well casing 43 as shown in the drawing and it will be desirable to provide suitable formation packers, such as indicated at 44, below the cementing device and above the liner.

The valve seats are made of soft brass or any other suitable material which may be easily drilled out after the cementation has been entirely completed.

I claim:—

1. A cementing device comprising a discharge section having an opening leading out through its lower end through which the cement is to be discharged and also having a plurality of spaced back pressure valves above the opening and cement discharge openings between the back pressure valves.

2. A cementing device comprising a discharge section having an opening leading out through its lower end through which the cement is to be discharged and also having a plurality of spaced back pressure valves above the opening, said discharge section also having cement discharging openings between the back pressure valves, and spring closed valves controlling said last-mentioned cement discharge openings.

3. A cementing device for use with well casings having a plurality of spaced seats and comprising a float valve assembly including a main valve co-operable with one of the seats, a stem connected with the said main valve, a movable flow controlled valve co-operable with the other seat, a coil spring between the valves, the valves being normally spaced by the coil spring at a dis-

tance greater than the distance between the seats, the entire valve assembly being lighter than the cement though heavier than the mud fluid, the fixed valve being slightly heavier than the cement and the movable valve being lighter than the cement.

4. A cementing device for wells comprising a discharge section having an opening leading out through its lower end and

through which the cement may be discharged, a back pressure valve above said opening, said discharge section also having peripheral discharge openings above said back pressure valve, and spring closed metal valves co-operable with said peripheral discharge opening. 10 15

ALEXANDER BOYNTON.
